UNITED STATES PATENT OFFICE.

ADOLPH A. THOMAS, OF CHICAGO, ILLINOIS, ASSIGNOR, BY MESNE ASSIGNMENTS, TO
WILLIAM R. HEATH, OF BUFFALO, NEW YORK.

AUTOMATIC TIME-ACCOUNTING DEVICE.

1,084,672.

Specification of Letters Patent.

Patented Jan. 20, 1914.

Application filed November 18, 1908. Serial No. 463,143.

To all whom it may concern:

Be it known that I, ADOLPH A. THOMAS, a citizen of the United States, residing at Chicago, in the county of Cook and State of Illinois, have invented certain new and useful Improvements in Automatic Time- Accounting Devices, of which the following is a full, clear, concise, and exact description, reference being had to the accompanying drawings, forming a part of this specification.

My invention relates to electrically operated time-accounting devices, and has for its object the provision of a mechanism for automatically taking account of a workman's time or wages. In devices of this kind, the arrangement is usually such that a workman's register is actuated periodically step by step, these periodic movements being controlled either by a clock directly or by some clock-governed motor.

In the prior art the mechanisms that are used for periodically actuating the registers are so constructed that the actuations occur either at the beginning of a periodic interval or at the end. For instance if a register is to be actuated every fifteen minutes, there would be four actuations every hour, no matter whether the actuations occur at the beginning of the quarter or at the end. Let it be supposed that the actuations take place at the beginning of the quarter hour. In this event for the hour, let us say, between seven and eight, the register would be actuated at 7.00, at 7.15, at 7.30 and at 7.45. By this arrangement it will be seen that the workman is credited with fifteen minutes in advance during every quarter of an hour. The result of this would be that should a workman disconnect his register at 11.46, he would be credited with the full quarter between 11.45 and 12.00, for the reason that the register was actuated at 11.45. On the other hand, should it be desired to escape this difficulty by causing the register to actuate at the end of a predetermined interval, so that the workman would be credited with a certain period only after such period had elapsed, then this difficulty arises: Let it be supposed that the beginning of the day's work is at 7.00 and that the workmen's registers are actuated at the end of every fifteen minutes, so that the first actuation would occur at 7.15. It is evident that the workman who

sets his register in operation any time before 7.15, as for instance at 7.14, would be credited with the full fifteen minutes between 7.00 55 and 7.15. From these illustrations it should be plain that no matter whether a register is actuated at the beginning of a predetermined 60 interval or at the end of such interval, it will be possible for a workman to credit himself with time and wages to which he is not entitled. Inventors along this line have recognized this difficulty and there are 65 patents in the art which show devices for causing registrations to be made at the beginning as well as at the end of periodic intervals, and subsequently making proper corrections for the over-actuations. A concrete example 70 will make clear just what is meant: Assuming that the register is to be operated once every fifteen minutes, then, according to certain of the devices in the prior art, such a register would be operated at 7.00, at 7.15, 75 at 7.30, at 7.45, and at 8.00. There would thus be five one-quarter hour actuations for every hour. The purpose of this is, of course, to compel the workman to throw in his register at the beginning of an interval, 80 and not to throw it out before the end of the interval, if he is to be credited with that interval. By the above arrangement, if a workman were to throw his register out of operation at any time between 7.45 and 8.00, 85 he would not be credited with that interval for the reason that there was no actuation at 8.00. Obviously the result of such an arrangement is that the workman's time and wage record at the end of the day is too 90 large. Accordingly, devices in which the actuations occur at the beginning and at the end of periodic intervals have auxiliary arrangements whereby the workman's record, at certain times, is run backward a sufficient 95 amount to make the proper corrections. This is, of course, an awkward and undesirable arrangement.

The object of my present invention is an electrically actuated device which operates 100 the register at the end of periodic intervals with the provision that the workman is required to close his switch at the beginning of an interval and to leave it in such closed position throughout the entire interval in 105 order that there may be an actuation of the register at the end of the interval. The result of this is that although there is but one

actuation during an interval, yet this actuation will not occur at the end of the interval unless the workman's switch has been closed at the beginning of the interval. Furthermore, according to my invention, if a workman should during an interval throw his switch into open position, the mechanism will be automatically restored to an inoperative position whereby it would not be actuated at the end of the interval during which the switch was thrown open. These and further objects and results of my invention will become apparent as the specification proceeds.

Referring to the accompanying drawings, wherein like characters refer to corresponding parts,—Figure 1 is a partly diagrammatic arrangement showing the structure and circuit connections of my mechanism; Fig. 2 is a fragmentary detail view showing the position that certain of the parts assume when the workman's switch or plug is in the open position; Fig. 3 is a modified form of circuit-closing device, as hereinafter explained; Fig. 4 is a modification of the arrangement shown in Fig. 1 whereby the automatic restoration of the parts to inoperative position upon the movement of the workman's switch to open position is accomplished by electromagnetic means; and Fig. 5 is a fragmentary detail view of the arrangement shown in Fig. 4, certain of the parts being shown in the position they assume upon the movement of the switch to open position.

Referring to Fig. 1, a ratchet wheel 1 suitably supported has rigidly connected therewith a gear wheel 2, which is shown as being in mesh with a gear 3. This gear 3 engages with the worm wheel 4, which in turn is shown as being connected with the register 5. Of course, it will be understood that this operative connection between the ratchet wheel 1 and the register 5 is more or less diagrammatic, and that any suitable connection may be employed whereby the movement of the ratchet wheel 1 will actuate a register. A bar or arm 6 is pivotally mounted at 7 upon the support 8. A pawl 9 pivotally mounted on the arm at 10 is arranged to engage with the teeth of the ratchet wheel, as shown. A spring 11 suitably mounted upon the support 8 normally tends to hold the arm 6 in the position in which it is shown in Fig. 1, a stop 12 limiting the inward movement of the arm. On the support 8 is also carried the electromagnet 13, with which an armature 14 on the lower end of the arm 6 co-operates to actuate the arm outwardly, that is, into the position in which it is shown in dotted lines, when the electromagnet is energized. This actuation of the arm 6 takes place only when the arm is in an unlocked position, in which position it is shown in Fig. 1. The outward

movement of the arm is limited by a stop 15. When the arm 6 is thus actuated by the electromagnet, the pawl 9 carries the ratchet wheel 1 in the direction indicated by the arrow for the distance of one tooth, whereby the register is actuated. Upon a support 16 is pivoted the locking dog or detent 17. The normal position of this detent is that shown in Fig. 2, that is to say,—normally the downwardly extending portion 18 on the detent engages with the top of the arm 6, whereby the latter is locked against movement. The detent 17 is provided with an armature 19 which co-operates with the electromagnet 20 to draw the detent 17 out of contact with the bar 6 when the electromagnet is energized. It will be observed that the detent 17 is at its outer end provided with an extension 21. When the detent 17 is in its normal or locking position, the extension 21 is below the lateral displacement or projection 22 on the spring 23. This spring is suitably supported at 24, and normally assumes the position in which it is shown in full lines in Fig. 1. Now, when the detent 17 is drawn upwardly by the electromagnet, the extension 21 will ride over the displacement 22 and force the spring into the position in which it is shown in dotted lines in Fig. 1, as indicated at 25. When the extension 21 has ridden past the projection 22, the spring will again assume its normal position, so that the extension 21 will at its outer end rest upon the displacement 22, as clearly shown in Fig. 1. From this it will be seen that when the detent 17 has once been drawn into its unlocking position it will be held in that position until released by means to be presently described. The movement of the detent 17 is limited by the stops 26 and 27. With so much of the description of the structural features of my device, let us now turn to the circuit arrangements. A suitable source of current 28, diagrammatically indicated in the drawings as a storage battery, has one side connected by the conductor 29 with the binding post 30. This binding post is on a support 31 which carries the spring contact 32. The other side of the battery is connected through a conductor 33 to the switch terminal 34. The other switch terminal 35 is connected with the conductor 36 which leads to the point 37. One end of the winding of the electromagnet 13 is connected through conductor 38 to the conductor segment 39 on the commutator or circuit-closer 40. The other end of the winding of the electromagnet 13 is connected through conductor 41 to the point 37. One end of the winding of electromagnet 20 is connected through conductor 42 to the conductor segment 43 of the circuit-closer 40. The other end of the winding of electromagnet 20 is connected through conductor 44 to the point 37. The

switch terminals 34 and 35 are adapted to be closed by the workman's switch 45, which in the drawings has, for the purpose of illustration, been shown in the form of a plug. 5 It is of course understood that any suitable form of switch may be employed. The circuit-closer 40 is shown in the form of an insulating disk secured to a shaft 46. This shaft is time-controlled, and is adapted to 10 be oscillated, so that during a predetermined interval the segment 39 will have traveled from the position in which it is shown in Fig. 1 to a position underneath the spring contact 32. Any suitable means 15 may be employed for producing such periodic rotation. In Fig. 1 I have shown an arm 47 secured to the shaft 46. This arm is provided with an extension 48 adapted to ride over the peripheral surface 49 of the 20 cam 50. This cam is adapted to be rotated by clockwork in the direction indicated by the arrow. It will be observed that during such rotation the extension 48 will ride up on the cam surface, whereby the shaft 46, 25 and with it the circuit-closer 40, will be moved forward slowly in an anti-clockwise direction during a predetermined interval, and suddenly backward at the end of an interval. 30 In order to understand best the operation of my device let it be assumed, for the sake of illustration, that the cam 50 makes one complete revolution every quarter of an hour. The angular position of the circuit-closer with respect to the contact 32 is that 35 shown in Fig. 1 at the beginning of an interval. The corresponding position of the arm 47 and the cam 50 is such that the extension 48 on the arm 47 will rest in the 40 lowermost portion of the cam surface. Let it be assumed that with the parts in this their initial or starting position, the switch 45 is in its closed position, as shown in Fig. 1. It should be remembered that the detent 45 17 will in this position of the parts be in its normal or locking position, as indicated in Fig. 2. Circuit will be completed through the electromagnet 20 as follows: from battery 28 to conductor 29, binding post 30, sup- 50 port 31, contact 32, segment 43, conductor 42, through the winding of electromagnet 20, conductor 44, conductor 36, across the terminals 35 and 34 of switch 45, conductor 33, back to the other side of the battery. 55 The energization of the electromagnet 20 will attract the armature 19, whereby the detent 17 will be moved out of contact with the bar 6, thus releasing or unlocking the latter. As above stated, when the detent 17 60 has been drawn into its releasing position, it will be held in that position by reason of the engagement between the extension 21 on the cam 50, ready to drop back into the lowermost portion to begin the next interval; so 65 that while the circuit-closer 40 is moved slowly from the position in which it is shown in Fig. 1 to a position in which the segment 39 will be under the contact 32, the reverse movement will take place almost in- 70

such that at the end of the interval (at the end of fifteen minutes in the example assumed) the segment 39 will be under the contact 32, whereby circuit will be closed through the electromagnet 13 as follows: 70 from one side of battery 28 to conductor 29, contact 32, segment 39, conductor 38, through the winding of electromagnet 13, conductor 41, conductor 36, across the switch terminals 35 and 34 of the switch 45, conductor 33, back to the battery. This energization of the electromagnet 13 causes the armature 14 on the arm 6 to be attracted, whereby the arm is actuated into the position in which it is partly indicated by the 80 dotted lines in Fig. 1. As above explained, this outward movement of the upper portion of the arm 6 will cause the pawl 9 to actuate the ratchet wheel 1 a distance of one tooth, whereby the register is actuated 85 through the connected gearing. It will be noted that the arm 6 is near its upper end provided with a lug 51. When the arm 6 is actuated, the outer end of this lug will come into contact with the lower end of the spring 23, forcing the latter into the position in which it is shown in dotted lines in 90 Fig. 1. The result of this deflection of the spring 23 is that the lateral projection 22 is moved from under the extension 21 on the 95 detent 17, permitting the detent to drop against the lower stop 27. Upon deenergization of the electromagnet 13, the spring 11 will force the arm inwardly back to its initial position. During this inward movement the curved surface 52 on the upper end of the arm 6 will ride over the correspondingly curved surface 53 on the extension 18 of the detent 17. This will of course raise 100 the detent 17, but only a slight amount not sufficient to carry the extension 19 on the 105 detent past the lateral displacement 22 on the spring 23, so that when the arm 6 has been moved to its initial position by the spring 11 the detent 17 will lock the arm, as clearly shown in Fig. 2. It will be seen 110 from this that when the arm 6 is actuated, the detent 17 is automatically restored to its locking position, and that when the arm 6 is moved inwardly upon deenergization of 115 the electromagnet 13 it will become immediately locked against further movement until again released through the action of the electromagnet 20 at the beginning of the next succeeding interval. When at the end of the 120 interval the segment 39 is under the brush or contact 32, the extension 48 on the arm 47 will be upon the uppermost portion of the cam 50, ready to drop back into the lowermost portion to begin the next interval; so 125 that while the circuit-closer 40 is moved slowly from the position in which it is shown in Fig. 1 to a position in which the segment 39 will be under the contact 32, the reverse movement will take place almost in- 130

stantaneously at the end of the predetermined interval, whereby the circuit-closing device is restored to the position in which it is shown in Fig. 1, ready to begin the next interval. Suppose now that a workman should remove his switch during an interval. At any time during such interval the detent 17 will be held in its unlocking position shown in Fig. 1, for the reason that, as just 10 explained, the electromagnet 20 will have been actuated at the beginning of the interval to draw the detent into its unlocking position. Should the workman draw his plug from the closed position in which it is 15 shown in Fig. 1 to the open position in which it is shown in Fig. 2, the extension 54 on the plug will carry with it the spring 23 into the position in which it is shown in dotted lines in Fig. 1 and in full lines in 20 Fig. 2. A hook portion 55 on the end of the extension 54 engages the spring 23 and draws the latter with it when the plug is withdrawn. This movement of the spring 23 into the position in which it is shown in 25 Fig. 2 upon movement of the switch to open position will, of course, permit the locking detent to drop into its normal or locking position, as shown in Fig. 2. It will thus be seen that the opening of the switch automatically places the arm 6 in a locked or inoperative position, so that should the workman again close the switch during that same interval there would be no actuation of the arm 6 at the end of that interval because of 30 the arm being locked. In this way, if a workman is to be credited for an interval, it is necessary that he close his switch at the beginning of the interval and leave it in such closed position during the entire interval. If a workman should be late in the morning and close his switch, say, a little 35 after 7.00, when he is required to report promptly at 7.00, then (in the example above used) there will be no actuation of his 40 register at 7.15, which is the end of the first interval, for the reason that the electromagnet 20 was not energized at the beginning of the interval, that is at 7.00, to release the arm 6. Similarly, should a 45 workman open his switch before the end of an interval, as for instance at 11.58, he would receive no credit during the interval between 11.45 and 12.00, for the reason that the register would not be actuated for that 50 interval before 12.00.

In lieu of the oscillating circuit-closer 40, one might employ the modified form of circuit-closer which I have shown in Fig. 3, whereby the same may be continuously rotated in one direction, instead of oscillated. This modified form of circuit-closer consists of an insulating disk 56 provided with two sets of contact segments. One set comprises the segments 57, 58, 59 and 60, while the 55 other set comprises the segments 61, 62, 63

and 64. The segments 57, 58, 59 and 60 are connected together by suitable conductors, shown diagrammatically at 65. The segments 61, 62, 63 and 64 are connected together by a conductor 66, which, in Fig. 3, has been conveniently shown in the form of a ring. It will thus be seen that by substituting the circuit-closer 56 in place of the circuit-closer 40 in Fig. 1, the same result may be attained by continuously rotating the shaft 46 at the proper predetermined speed. As in the example above assumed, let it be supposed that an interval is to consist of fifteen minutes. Then the circuit-closer 56 would be so arranged on the shaft 46 that at the beginning of an interval the contact brush 32 would be upon the segment 61. By connecting the common conductor 66 with the conductor 42, circuit will at the beginning of that interval be established through the electromagnet 20, as heretofore explained. The shaft 46 is rotated at such a speed that after fifteen minutes the contact 32 will be upon the segment 58. Now, by connecting the common conductor 65 with the conductor 38, it will be seen that at the end of the interval, circuit will be established through the electromagnet 13, just as it was with the employment of the oscillating circuit-closer 40. The distance between the segment 58 and the segment 62 (or, generally speaking, the distance between any segment of the first set and its immediately adjacent segment of the second set) is such that almost instantaneously after the contact 32 has left the segment 58 it will make contact with the segment 62 at the beginning of the next interval, in order to close the circuit through the electromagnet 20. In other words, the interval represented in Fig. 1 by the arm 47 dropping from its uppermost to its lowermost position is in Fig. 3 represented by the interval during which the contact 32 would leave segment 58 and engage segment 62.

It will of course be understood that the two forms of time-controlled circuit-closers herein shown are merely for the sake of illustration, and other forms equally well adapted to the purpose might suggest themselves to those skilled in the art.

From the description of the operation of the arrangement shown in Figs. 1 and 2, it will be seen that upon the movement of the switch from closed to open position the detent will be restored to its locking position by means solely mechanical.

In the modified arrangement illustrated in Figs. 4 and 5, I have shown electrically-operated means for restoring the detent 17 to its locking position when the workman's switch is moved to open position. The form of switch shown in Figs. 4 and 5 has two connecting portions 67 and 68. When the switch is in its closed position, as shown in 120

Fig. 4, the connecting portion 67 spans the switch terminals 35 and 34. As explained in connection with Fig. 1, with the switch in its closed position, the electromagnet 20 will at the beginning of an interval be energized to draw the detent 17 into unlocking position. In Fig. 4 the detent is shown in such unlocking position, being held therein by the spring 23, all as previously explained. Suppose that the workman should move his switch to open position, that is to say, into the position in which it is shown in Fig. 5. Upon a comparison of the two positions of the switch, as shown in these two figures, it will be observed that during the movement of the switch from one position to the other, the connecting portion 68 will span the terminals 69 and 70. When this takes place, circuit through the electromagnet 72 is established as follows: from one side of battery 28, conductor 29, conductor 73, terminal 70, connecting portion 68, terminal 69, conductor 74, through the winding of the electromagnet 72, conductor 75, conductor 33, back to the other side of the battery. This energization of the electromagnet 72 attracts the armature 76 carried on the spring 23, whereby the latter is deflected toward the electromagnet 72. This deflected position of the spring 23 is precisely the same as that shown in dotted lines in Fig. 1 or in full lines in Fig. 2. When so deflected the spring 23 permits the detent 17 to drop into its locking position, as shown in Fig. 5. The switch shown in Figs. 4 and 5 may be so arranged that it will not remain in the position in which the connecting portion 78 spans the terminals 69 and 70, in order to prevent closing of the circuit through the electromagnet 72 for an unnecessary length of time. Any suitable spring attachment may be devised for compelling movement of the switch so that the connecting portion 68 will when the switch is in its closed position be moved beyond the terminals 69 and 70, as shown in Fig. 5.

While I have shown my invention in two specific forms, I would have it understood that such illustration is merely by way of example, and that many modifications may be resorted to in various details and still include the essence of my invention.

Having thus described my invention, what I desire to claim as new and secure by Letters Patent of the United States, is:

1. In a register-actuating device, the combination of a ratchet wheel, electrically operated mechanism for periodically actuating the same at the end of predetermined intervals, means for normally holding said mechanism in an inoperative position, and electromagnetic means energized at the beginning of an interval to actuate said holding means, whereby said mechanism may be operated at the end of an interval.

2. In a register-actuating device, the combination of a ratchet wheel, electrically operated mechanism for periodically actuating the same at the end of predetermined intervals, locking means for normally preventing operation of said mechanism, and an electromagnet adapted to be energized at the beginning of an interval to disengage said locking means from said mechanism to permit actuation of said mechanism at the end of the interval.

3. In a register-actuating device, the combination of a ratchet wheel, a pivoted arm associated therewith, a pawl carried by said arm to actuate said ratchet wheel, a register adapted to be actuated by the movement of said ratchet wheel, means for normally holding said arm in a locked position, electromagnetic means for periodically actuating said arm at the end of predetermined intervals, and electromagnetic means actuated at the beginning of an interval to render said locking means ineffective during the interval, whereby actuation of said arm is permitted at the end of the interval to operate the ratchet wheel.

4. In a register-actuating device, the combination of a ratchet wheel, a pivoted arm associated therewith, a pawl carried by said arm to actuate said ratchet wheel, a register adapted to be actuated by the movement of said ratchet wheel, a detent normally engaging said arm to hold it in a locked position, an electromagnet adapted to be periodically energized at the beginning of predetermined intervals to disengage said detent from said arm, and electromagnetic means adapted to actuate said arm at the end of an interval, provided said arm has been unlocked at the beginning of the interval.

5. In a register-actuating device, the combination of a ratchet wheel, electrically operated mechanism for periodically actuating the same at the end of predetermined intervals, locking means for normally preventing operation of said mechanism, an electromagnet adapted to be energized at the beginning of an interval to disengage said locking means from said mechanism to permit actuation of said mechanism at the end of the interval, and means for automatically restoring said locking means to its operative position when said mechanism is actuated.

6. In a register-actuating device, the combination of a ratchet wheel, a pivoted arm associated therewith, a pawl carried by said arm to actuate said ratchet wheel, a register adapted to be actuated by the movement of said ratchet wheel, means for normally holding said arm in a locked position, electromagnetic means for periodically actuating said arm at the end of predetermined intervals, electromagnetic means ac-

5 tuated at the beginning of an interval to render said locking means ineffective during the interval, whereby actuation of said arm is permitted at the end of the interval to operate the ratchet wheel, and means for automatically restoring said locking means to its operative position when said arm is actuated.

7. In a register-actuating device, the 10 combination of a ratchet wheel, a pivoted arm associated therewith, a pawl carried by said arm to actuate said ratchet wheel, a register adapted to be actuated by the movement of said ratchet wheel, a detent 15 normally engaging said arm to hold it in a locked position, an electromagnet adapted to be periodically energized at the beginning of predetermined intervals to disengage said detent from said arm, electromagnetic means adapted to actuate said arm at the end of an interval, provided said arm has been unlocked at the beginning of the interval, and means for automatically 20 restoring said detent to its locking position when said arm is actuated.

8. The combination of a register, mechanism for operating the same, electromagnetic means adapted to be energized at the end of periodic intervals for actuating said 30 mechanism, locking means engaging said mechanism for normally preventing operation thereof, and electromagnetic means adapted to be energized at the beginning of an interval to disengage said locking means 35 from said mechanism to permit actuation of said mechanism at the end of the interval.

9. The combination of a register, mechanism for operating the same, electromagnetic means adapted to be energized at the 40 end of periodic intervals for actuating said mechanism, locking means engaging said mechanism for normally preventing operation thereof, electromagnetic means adapted to be energized at the beginning of an interval to disengage said locking means from said mechanism to permit actuation of said mechanism at the end of the interval, and means for restoring said mechanism to its locked position upon deenergization of said 45 first-mentioned electromagnetic means.

10. In a register-actuating device, the combination of a ratchet wheel, a pivoted arm associated therewith, a pawl carried by said arm to actuate said ratchet wheel, a 50 register adapted to be actuated by the movement of said ratchet wheel, means for normally holding said arm in a locked position, electromagnetic means for periodically actuating said arm at the end of predetermined 55 intervals, electromagnetic means actuated at the beginning of an interval to render said locking means ineffective during the interval, whereby actuation of said arm is permitted at the end of the interval to operate 60 the ratchet wheel, and means for automatically

65 cally restoring said arm to its locked position upon deenergization of said first-mentioned electromagnetic means.

11. In a register-actuating device, the 70 combination of a ratchet wheel, a pivoted arm associated therewith, a pawl carried by said arm to actuate said ratchet wheel, a register adapted to be actuated by the movement of said ratchet wheel, a detent normally 75 engaging said arm to hold it in a locked position, an electromagnet adapted to be periodically energized at the beginning of predetermined intervals to disengage said detent from said arm, electromagnetic means adapted to actuate said arm at the end of an interval, provided said arm has been unlocked at the beginning of the interval, and means for automatically 80 restoring said arm to its locked position upon deenergization of said electromagnetic 85 means.

12. In a register-actuating device, the combination of a ratchet wheel, a pivoted arm associated therewith, a pawl carried by 90 said arm to actuate said ratchet wheel, a register adapted to be actuated by the movement of said ratchet wheel, a detent normally engaging said arm to hold it in a locked position, an electromagnet adapted to be periodically energized at the beginning 95 of predetermined intervals to disengage said detent from said arm, means for holding said detent in its disengaged position, electromagnetic means adapted to actuate said arm at the end of an interval, and means 100 for automatically restoring said detent to its locking position when said arm is actuated.

13. In a register-actuating device, the combination of a ratchet wheel, a pivoted arm 105 associated therewith, a pawl carried by said arm to actuate said ratchet wheel, a register adapted to be actuated by the movement of said ratchet wheel, a detent normally engaging said arm to hold it in a locked position, an electromagnet adapted to be periodically 110 energized at the beginning of predetermined intervals to disengage said detent from said arm, means for holding said detent in its disengaged position, electromagnetic means adapted to actuate said arm at the end of an interval, means for automatically 115 restoring said detent to its locking position when said arm is actuated, and means for restoring said arm to its locked position upon deenergization of said electromagnetic means.

14. In a register-actuating device, the combination of a pivoted arm, means for normally holding the same locked against actuation, an electromagnet for moving said locking means upon energization to unlock said arm, and an electromagnet for actuating said arm to operate the register. 125

15. In a register-actuating device, the combination of a movable arm, means for 130

locking the same, a pair of electromagnets associated therewith, one of said electromagnets being adapted to actuate said arm, and means whereby the other of said electromagnets controls said locking means to permit or to prevent actuation of said movable arm.

16. In a register-actuating device, the combination of a movable arm, a pair of electromagnets associated therewith, energizing circuits for said electromagnets, a switch for controlling said circuits, means whereby said electromagnets must be energized alternately to actuate said arm for operating the register, and means whereby the opening of said switch prevents the operation of said arm upon the next succeeding energization of either of said electromagnets, when the switch is closed again.

17. The combination with register-operating mechanism, of a pair of electromagnets, energizing circuits therefor, a switch for controlling said circuits, means requiring said electromagnets to be energized alternately for actuating said mechanism, and means whereby the opening of said switch prevents the operation of said mechanism upon the next succeeding energization of either of said electromagnets, when the switch is closed again.

18. In a register-actuating device, the combination of a register, a movable arm, means for normally locking the same, an electromagnet for controlling said locking means, a second electromagnet for actuating said arm when unlocked, circuits for energizing said electromagnets, a time-controlled circuit-closer for periodically closing the circuit through said first-mentioned electromagnet at the beginning of predetermined intervals, whereby said locking means releases said arm, means for holding said locking means in its releasing position during an interval, said circuit-closer causing said second electromagnet to be energized at the end of an interval, whereby said arm is actuated to operate the register, and means for automatically restoring said arm to its locked position upon deenergization of said second electromagnet.

19. In a register-actuating device, the combination of a pivoted arm having a pawl, a ratchet wheel adapted to be actuated by said pawl, a register connected with said ratchet wheel to be operated thereby, a detent for normally holding said arm locked, an electromagnet for disengaging said detent from said arm to unlock the same, a second electromagnet for actuating said arm when unlocked, circuits for energizing said electromagnets, a time-controlled circuit-closer for periodically closing the circuit through said first-mentioned electromagnet at the beginning of predetermined intervals, whereby said detent releases said arm, means for

holding said detent in its unlocking position during an interval, said circuit-closer causing said second electromagnet to be energized at the end of an interval, whereby said arm is actuated to operate the register, and means for automatically restoring said arm to its locked position upon deenergization of said second electromagnet.

20. In a register-operating mechanism, the combination of an actuating arm, means for normally holding the same locked, an electromagnet for moving said locking means to releasing position, an energizing circuit for said electromagnet, a switch in said circuit, a time-controlled circuit-closer for periodically closing the circuit through said electromagnet at the beginning of predetermined intervals, when said switch is closed, to unlock said arm, means for holding said locking means in its releasing position, and means for automatically restoring said locking means to normal position upon opening of said switch.

21. In a register-operating mechanism, the combination of an actuating arm, a detent normally engaging said arm to hold the same locked, an electromagnet for disengaging said detent from said arm to unlock the same, an energizing circuit for said electromagnet, a switch in said circuit, a time-controlled circuit-closer for periodically closing the circuit through said electromagnet at the beginning of predetermined intervals, when said switch is closed, to unlock said arm, means for holding said detent in its unlocking position, and means for automatically restoring said detent to its normal or locking position upon opening of said switch.

22. In a register-operating mechanism, the combination of an actuating arm, means for normally holding the same locked, an electromagnet for moving said locking means to releasing position, an energizing circuit for said electromagnet, a switch in said circuit, a time-controlled circuit-closer for periodically closing the circuit through said electromagnet at the beginning of predetermined intervals, when said switch is closed, to unlock said arm, means for holding said locking means in its releasing position, and electromagnetic means for automatically restoring said locking means to normal position upon opening of said switch.

23. In a register-operating mechanism, the combination of an actuating arm, a detent normally engaging said arm to hold the same locked, an electromagnet for disengaging said detent from said arm to unlock the same, an energizing circuit for said electromagnet, a switch in said circuit, a time-controlled circuit-closer for periodically closing the circuit through said electromagnet at the beginning of predetermined intervals,

when said switch is closed, to unlock said arm, means for holding said detent in its unlocking position, and electromagnetic means for automatically restoring said detent to its normal or locking position upon opening of said switch.

24. In a register-operating mechanism, the combination of an actuating arm, means for normally holding the same locked, an electromagnet for moving said locking means to releasing position, means for holding said locking means in such position, a second electromagnet associated with said arm for actuating the same, energizing circuits for said electromagnets, a switch for said circuits, a time-controlled circuit-closer for periodically closing the circuit through said releasing electromagnet at the beginning of predetermined intervals and through said actuating electromagnet at the end of said intervals, when said switch is closed, means for automatically restoring said arm to its locked position upon deenergization of said actuating electromagnet, and means for automatically restoring said locking means to normal position upon opening of said switch.

25. In a register-operating mechanism, the combination of an actuating arm, means for normally holding the same locked, an electromagnet for moving said locking means to releasing position, means for holding said locking means in such position, a second electromagnet associated with said arm for actuating the same, energizing circuits for said electromagnets, a switch for said circuits, a time-controlled circuit-closer for periodically closing the circuit through said releasing electromagnet at the beginning of predetermined intervals and through said actuating electromagnet at the end of said intervals, when said switch is closed, means for automatically restoring said arm to its locked position upon deenergization of said actuating electromagnet, and electromagnetic means for automatically restoring said locking means to normal position upon opening of said switch.

26. In a register-operating mechanism, the combination of an actuating arm having a pawl, a ratchet wheel adapted to be actuated by said pawl, a register connected with said ratchet wheel to be operated thereby, a pivoted detent for normally holding said arm locked, an electromagnet for moving said detent to releasing position, spring means for holding said detent in such position, a second electromagnet associated with said arm for actuating the same, energizing circuits for said electromagnets, a switch for said circuits, a time-controlled circuit-closer for periodically closing the circuit through said releasing electromagnet at the beginning of predetermined intervals and through said actuating electromagnet at the end of

said intervals, when said switch is closed, means for automatically restoring said arm to its locked position upon deenergization of said actuating electromagnet, and means for automatically restoring said detent to locking position upon opening of said switch.

27. In a register-operating mechanism, the combination of an actuating arm having a pawl, a ratchet wheel adapted to be actuated by said pawl, a register connected with said ratchet wheel to be operated thereby, a pivoted detent for normally holding said arm locked, an electromagnet for moving said detent to releasing position, spring means for holding said detent in such position, a second electromagnet associated with said arm for actuating the same, energizing circuits for said electromagnets, a switch for said circuits, a time-controlled circuit-closer for periodically closing the circuit through said releasing electromagnet at the beginning of predetermined intervals and through said actuating electromagnet at the end of said intervals, when said switch is closed, means for automatically restoring said arm to its locked position upon deenergization of said actuating electromagnet, and electromagnetic means for automatically restoring said detent to locking position upon opening of said switch.

28. In a register-operating mechanism, the combination of a movable arm, means for normally holding the same locked, an electromagnet for moving said locking means into releasing position, means for holding said locking means in such position, an energizing circuit for said electromagnet, a switch for said circuit, and means for automatically restoring said locking means to normal position upon opening of said switch.

29. In a register-operating mechanism, the combination of a movable arm held normally in an inoperative position, a pair of electromagnets associated therewith, energizing circuits for said electromagnets, and means whereby the energization of one of said electromagnets places said arm in an operative position, while the energization of the other electromagnet actuates said arm to operate the register.

30. The combination of register-actuating mechanism held normally in an inoperative position, electromagnetic means operated at the beginning of predetermined intervals to place said mechanism in an operative position, and electromagnetic means adapted to be operated at the end of an interval to actuate said mechanism.

31. The combination of register-actuating mechanism, means for normally holding the same locked against operation, an electromagnet adapted to be energized at the beginning of predetermined intervals for mov-

ing said locking means into releasing position, said locking means being held in such position during the interval, and an electromagnet adapted to be energized at the end 5 of an interval to actuate said mechanism.

32. The combination of register-actuating mechanism, means for normally holding the same locked against operation, electromagnetic means for periodically actuating said 10 mechanism at the end of predetermined intervals, and electromagnetic means actuated at the beginning of an interval to render said locking means ineffective during the interval, whereby actuation of said 15 mechanism is permitted at the end of the interval.

33. The combination of register-actuating mechanism, means for periodically actuating the same at the end of predetermined 20 intervals, means for normally preventing operation of said mechanism, electromagnetic means adapted to be actuated at the beginning of an interval to permit actuation of said mechanism at the end of the interval, 25 and means for automatically restoring said preventing means to operative position immediately upon actuation of said mechanism.

34. The combination of register-actuating 30 mechanism, a pair of electromagnets associated therewith, means requiring said electromagnets to be energized alternately to actuate said mechanism, and means whereby the deenergization of either of said electromagnets causes said mechanism to become 35 locked.

35. The combination of register actuating 40 mechanism, electromagnetic means for controlling the actuating mechanism to advance the register a desired amount in a given

time, and devices for locking the said actuating mechanism after each actuation.

36. The combination of a register-actuating mechanism, means for normally holding the same locked against operation, electromagnetic means for actuating said mechanism when unlocked, a switch in the energizing circuit of said electromagnetic means, and means for automatically restoring said mechanism to locked position upon opening 45 of the switch. 50

37. In combination, a register, electromagnetic means for operating the register, locking devices, and an electromagnet for moving the locking devices to releasing position. 55

38. In combination, a register, actuating mechanism, and electro-magnetic devices for locking and unlocking said mechanism for each operation of the register. 60

39. In combination, a register, actuating mechanism, electro-magnetic mechanism for determining operative and inoperative intervals for said mechanism, and devices for locking and unlocking said mechanism for 65 each operation of the register.

40. In combination, a register, actuating mechanism, electro-magnetic mechanism for determining operative and inoperative intervals for said mechanism, and electromagnetic devices for locking and unlocking said mechanism for each operation of the register during 70 said operative intervals.

In witness whereof, I hereunto subscribe my name this 16th day of November, 1908. 75

ADOLPH A. THOMAS.
